At this

UNITED STATES PATENT OFFICE.

WILLIAM I. BUNKER, OF LA GRANGE, ILLINOIS.

DESIGN FOR A BICYCLE-SADDLE.

SPECIFICATION forming part of Design No. 25,590, dated June 2, 1896.

Application filed October 22, 1895. Serial No. 566,562. Term of patent 7 years.

To all whom it may concern:

Be it known that I, WILLIAM I. BUNKER, a citizen of the United States, residing at La Grange, Cook county, Illinois, have invented and produced a new and original Design for Bicycle-Saddles, of which the following is a specification, reference being had to the accompanying drawings, forming a part hereof.

In the accompanying drawings, Figure 1 represents a plan view of my design, looking at it from the top; and Fig. 2, a transverse section taken on line 2 of Fig. 1.

The leading feature of my design consists in a saddle-body having a central portion and extending projecting portions which, when viewed in plan view, resemble a star.

A is the body portion of the seat or saddle, provided with the projecting portions a , a' , and a'' .

In the cross-section B represents the supporting-frame, b the socket, and b' the setscrew, the whole presenting to the eye a handsome and ornate figure.

What I claim is—

The design for a bicycle-saddle herein shown and described.

WILLIAM I. BUNKER.
